SLUB CATCHER

Robert V. Olson, Attleboro, Mass., assignor to
Mossberg Pressed Steel Corporation, a corpora-
tion of Massachusetts

Application May 7, 1938, Serial No. 206,653

11 Claims. (Cl. 28—64)

This invention relates to a slub catcher; and has for one of its objects the provision of a device which will detect slubs or bunches in yarn and cause a severance of the yarn that a less conspicuous knot may be tied rather than the imperfect yarn be passed on to be woven to form cloth.

Another object of the invention is the provision of a device which while functioning to detect the presence of a slub or bunch in the yarn to also shave off any fly or lint which may extend from the yarn as it passes therethrough.

Another object of the invention is a provide a slub catcher or detector which will operate positively to break the yarn at the location of a slub by means of a separate and individual blade member or the like movable into engagement with the yarn rather than the use of the member itself through which the yarn normally travels in its path of movement to cause such severance.

Another object of the invention is the provision of a guard which will prevent engagement of the yarn with the portion which causes it to be severed until some bunch or slub is presented, thus preventing any unnecessary abrading of the yarn.

Another object of the invention is to hold the cutter blade out of a position for engagement with the yarn by use of a spring of such tension that it will permit the cutter blade to be readily moved into operating position.

Another object of the invention is to provide a detector blade which will swing to accommodate itself to varying positions of the yarn with reference to the build-up of the package to which it is being delivered.

Another object of the invention is to provide a detector blade through which the yarn moves which will swing to a position for easy threading when no yarn is running through the same.

Another object of the invention is to provide a detachable detector blade and one which may be easily and quickly assembled and at a minimum expense.

With these and other objects in view, the invention consists of certain novel features of construction, as will be more fully described, and particularly pointed out in the appended claims.

In the accompanying drawings:

Fig. 1 is a perspective view of the device mounted in position for operation on the guide bar shown in dotted lines over which the yarn usually travels;

Fig. 2 is an elevational view looking at the

same side of the device or the front thereof, as shown in Fig. 1, but illustrating more definitely the relative position of the parts;

Fig. 3 is a central sectional view on substantially line 3—3 of Fig. 1;

Fig. 4 is a perspective view of the frame and nipper blade guard with the nipper blade removed;

Fig. 5 is a perspective view of the detector blade;

Fig. 6 is a perspective view of one section of the detector blade;

Fig. 7 is a perspective view of another section of the detector blade;

Fig. 8 is a sectional view of the saddle;

Fig. 9 is a sectional view of the saddle taken on line 9—9 of Fig. 8;

Fig. 10 is a fragmental side elevation showing the nipper blade and stop therefor;

Fig. 11 is a front elevational view of a modified form of slub catcher device;

Fig. 12 is a section on line 12—12 of Fig. 11;

Fig. 13 is a front elevational view of a still different modification of a slub catcher;

Fig. 14 is an elevation of the detector blade of Fig. 13;

Fig. 15 is an elevation of a modified form of detector blade;

Fig. 16 is a perspective view of a part of the blade of Fig. 15.

The tendency at the present time is to be more critical of the fabrics that are woven, and accordingly more care and accuracy in the preparation of the yarn for the finished fabric must be had. In the use of slub catchers there is usually provided a blade which shaves off lint or small projections from the yarn as it passes therethrough.

A bunch or slub or imperfection in the yarn is frequently housed within the fibers so that the good and strong fibers are on the outside while the imperfection or bunch caused by some foreign particle is located within the yarn and is completely housed by these good fibers, consequently the good fibers will be shaved off at the bunch leaving an imperfect and weak

yarn. It is more desirable that such bunch cause the yarn to break and the ends be pieced by knotting rather than such a condition happening.

It is also desirable that the yarn be rather accurately sized as to a maximum diameter. Further, it is desirable that the part that breaks the yarn be a part with which the yarn does not engage to be abraded thereby, and I have arranged a slub catcher obviating these undesirable

features by providing that a detector accurate to

less than a thousandth of an inch be provided through which the yarn passes, and so arranged that should a bunch or slub occur in the yarn the detector will cause some other part to move, 5 with which the yarn does not engage in its normal passage, which will nip the yarn and cause the yarn to break, thus permitting it to be pierced up and a more perfect and stronger yarn provided than heretofore.

10 Further, I have provided that the detector blade through which the yarn passes in its normal run will be so swung that should the yarn not be running therethrough it will move to a position for very easy threading; and I have 15 further provided that this detector blade be such that it may very readily be changed and a different one substituted therefor for a change in size of yarn which may be run; and the following is a more detailed description of the present 20 embodiment of this invention, illustrating the preferred means by which these advantageous results may be accomplished:

With reference to the drawings, 15 designates a mounting bar or part of the usual winding machine over which the yarn 16 travels. The slub catcher which I have provided is mounted upon this bar 15 and consists of a framework comprising a sheet metal body structure in the form of a vertical plate 17 which has a narrower strip 30 bent forwardly as at 18 to provide a horizontal portion 19 and then bent as at 20 to provide a downwardly extending leg 21 with an arcuate recess 22, thence bent as at 23 to extend rearwardly as at 24 and then upwardly as at 25 to be joined 35 in the vicinity of portion 26 to the plate 17 as a brace. A complementary member 27 having an opening 28 to engage a cut-out and raised hook 29 cooperates with the arcuate portion 22, while a screw 30 extending through an opening in this 40 member 27 and into a threaded opening 31 in the portion 21 serves to mount this body or framework upon the bar 15.

A block 32 is firmly secured within the triangular framework above described, such for instance 45 as by welding it therein, and supports a contact bar 33 extending therefrom and also a nipper blade guard 34 having both of its legs 35 and 37 mounted as at 36 in this block.

A nipper blade 40 consists of a thin or light 50 weight sheet of steel with a sharpened edge 42 and is of a horizontal length greater than any traverse that the yarn may have across the contact bar 33. At intervals along its length as at 43 this blade is cut and pressed out while 55 also at intervals 44 in the body plate 17 the stock is cut and similarly pressed out. These pressed out portions form eyes for the reception of a pivot pin 45 extending through the pressed out eyes 43 and 44 to swingably mount the nipper blade 40 in position. This nipper blade is of a vertical depth so that when it swings on its pivot rearwardly, it will engage the contact bar 33 at a flattened portion 39 thereof so as to bind or nip and cut off a piece of yarn at this point of engagement. A spring 46 encircles this pin with one end 47 engaging the frame 17, while the other end 48 engages the nipper blade which causes the nipper blade to swing about its pivot pin 45 forwardly away from the bar, in which angular 65 position of the nipper blade its operating edge is lifted out of contact with the yarn when the yarn 16, see particularly Fig. 3, draws over the bar 33 from the rod 15. The yarn is out of contact with the arms 35 and 37 of the guard 34 but should it tend to raise at the top of the 70

traverse it would be prevented from raising to a position to engage the sharpened edge 42 of the nipper blade by the arms 35 and 37, as shown in Fig. 3, and thus will prevent any abrading of the yarn which might otherwise occur should the 5 yarn draw over this cutting edge.

The nipper blade 40 is limited in its movement about its pivot pin 45 under action of spring 46 by a finger 49 which extends outwardly from the frame plate 17 to hook about the side edge of the 10 nipper blade so as to engage the same and hold it in substantially the position shown in Fig. 3. The tension on the spring 46 may be adjusted by withdrawing the pin and winding the spring to provide more convolutions and then returning 15 the pin.

Beneath the overhanging guard lip 50 on the plate 17 the stock of the plate is drawn or cupped rearwardly as at 51. A pin 52 has a reduced end 53 with its shoulder portion 54 so formed engaging the bottom of this cup 51 while its reduced end 53 extends through the bottom of the cup and is riveted over as at 55 to mount it firmly in position. A saddle designated generally 56 consists of a back wall 57 with flanges 58 extending from the back wall which are slit to provide resilient fingers 59 which flare outwardly at their outer ends, while a bushing 60 extends from the wall 57 and is provided with a bore 61 to be rockably mounted upon the pin 52. The 30 head 62 of the pin 52 maintains the saddle in position. A spring 63 encircles the stud 60 with one end 64 extending into an opening of the cup recess 51, while the other end 65 of the spring extends into a selected opening 65' in the rear 35 wall of the saddle to hold it in position, with the adjusted tension depending on the hole selected. This spring tends to swing the saddle about its pivotal mounting on the pin 52.

A stop pin 120 is either raised from the stock of 40 the plate 17 or provided as an additional member supported on the plate at a location to engage the downwardly extending portion 121 of the saddle so as to limit the position of this saddle should the detector blade be removed therefrom. 45 Thus, the saddle is always in a convenient position for replacing of the detector blade which may be performed by one hand of the operator.

The detector blade designated generally 66 is 50 rockably mounted on an axis at right angles to the axis of pin 52 in the saddle. This blade is provided at its upper end with arms 67 and 68 which may be sprung toward each other by reason of the Y-shaped formation and which will engage in rounded sockets 69 in the resilient fingers 59 55 by reason of the ends being correspondingly rounded or spherical shaped. This blade is made in two sections, one section 70 being straight with a hardened and ground inner surface, while the other section 72 is notched as at 73 in a desired 60 amount so that when these two sections are placed together a slot 74 will be provided between them of a desired dimension which may be for illustration ten thousandths of an inch. Similar other blades may be provided with a slot or space of, 65 for example, fifteen thousandths of an inch where yarn of this diameter is being used and the blades may be colored for convenience in designation one from the other and may be interchanged at will as desired. The two sections are held together by spring bands 75 and 76 which seat in notches 77, 78 and 79, 80 in the two sections. The resilient fingers enable the blade to be positioned in the saddle by its first being positioned under guard 37 and then snapped into the fingers. 70 75

In Figs. 15 and 16 I have illustrated a modified form of detector blade which I will designate generally 105. This detector blade consists of two sections 106 and 107 which are offset at their upper portions as at 108 and 109 so as to provide a space or fork-like formation. The out-turned ends 110 and 111 are of a size and shape to fit within the resilient fingers 59 of the saddle. The main shank portions of these blades are straight with the section 107 shorter than the section 106 in a manner similar to one section being shorter than the other, as previously described in the other form of structure. However, instead of notching one end of the shorter section, as in the first form described, I provide a spacing element 112 which is of such a thickness that the space or gauge 113 of the blade is accurately provided. This spacing element 112 has extensions 114 and 115 which extend beneath the ring-like wire securing means 116 and 117 which secure the sections and spacing element 112 together. This spacing element is provided with a handle portion 118 for convenience in positioning the detector blade in position. Blades having spacing members of a different dimension may be formed in the same way as that here illustrated for the forming with identical sections of a variety of sizes similarly to that heretofore described in connection with the first-mentioned detector blade.

The spring 63 will swing the saddle and detector blade with it to the extreme position to the right, as shown in Fig. 2, and in this position the section 70 or 106 of the blade being longer than the section 72 or 107 will be such that the yarn may be readily threaded by sliding the yarn in along the contact bar 33, it being picked up by the extended portion 71 or 119 of the detector blade and guided inwardly and upwardly to the location where it will run for the beginning of packaging upon a spool, the blade swinging outwardly of the spool or to the right as viewed in Figs. 1 and 2, as the package builds up. Should a bunch or slab occur it will catch the edges of the slot 74 or 113 moving the detector blade rearwardly and the nipper blade with it into position against the contact bar 33 and cut off the yarn closely adjacent to the bunch which may be removed and the thread knotted and operation again resumed. The knots are less objectionable in fabric, whereas the bunches and slabs are objectionable and cause imperfect fabric to be formed.

The shape of the body plate 17 is such that yarn engaging the lip 50 will be guided by the edge of plate 17 out to the end of the guard 34, and then as the plate is shaped to be within the guard 34 at its end the yarn may be slid along the guard without any interruption. The short end of the detector blade is of a length so that it will not be engaged by the yarn sliding along the guard into engagement with the longer portion of the detector blade when the same is moving into position.

A further feature of the arrangement of the detector blade traversing back and forth along the nipper blade is that the rubbing of the detector blade on the edge of the nipper blade, as shown in Fig. 3, will serve to maintain the nipper blade always sharpened and thus a keen cutting edge is always provided.

In the modification of Figs. 11 and 12, the detector 80 comprises a sheet of stock having an opening 81 to loosely fit upon the shank 82 of a bolt or headed screw and is prevented from dis-

engagement therewith by the head 83 thereof. This bolt forms a pivotal mounting for the detector which is swung about the pivotal mounting 81 by a wire spring 84 having a coiled or loop portion 85 engaging the arm at the upper side of the pivot 81 as by the finger portion 86 thereof. The coil in the spring is sufficient to tend to swing the arm about the pivot point 81 to move the lower portion of the blade to the right, as viewed in Fig. 11, or in a position similar to the tendency 10 of the spring 63, previously described, to move the detector blade 66. This spring is held in position by being clamped by the head 87 of the bolt 88 positioned in the plate 17 while this spring continued on and is provided with an arcuate portion 89 and end 90 to engage the nipper blade 40 and force it about its pivotal mounting 45 against its stop 49 in a manner previously described. This detector blade 80 has an enlarged portion 91 and a bifurcated portion comprising arms 92 and 93 a little longer than the arm 92 for the engagement and guiding of the yarn 16 into the slot 94 between these arms 92 and 93 which are formed to provide the slot 94 of a definite width, such for instance as ten thousandths 25 of an inch, if this size of yarn should be run. Should a different size of yarn be operated upon the entire arm 80 will be interchanged with a different one having a different width slot.

In Fig. 13 I have illustrated a detector blade 30 95 which is offset as at 96 so as to provide a weighted portion which tends to swing the entire arm to the right, as shown in Fig. 13. Thus, no spring is needed for swinging this detector blade to such position. This detector blade 95 is provided with winged portion clamps 97 and 98 which bind arms 99 and 100 between them in a manner to provide a slot 101 for the yarn 16. Here again this entire arm would be interchanged with another arm by changing the screw mounting 102 40 therefor which fits loosely through a hole 103 in the detector blade, permitting it to rock toward the nipper blade 40 of the device, which blade is as previously set forth in connection with Figs. 1 to 10.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a slab catcher, a body frame having a contact bar over which the yarn is guided, a nipper blade mounted on said frame for movement toward said bar, a detector blade having an opening through which the yarn travels, means comprising resilient arms for detachably mounting said detector blade for movement toward said nipper blade to engage and move said nipper blade to sever the yarn.

2. In a slab catcher, a body frame having a contact bar over which the yarn is guided, a nipper blade mounted on said frame for movement toward said bar, and a detector blade having an opening through which the yarn travels, said nipper blade being beveled to provide its cutting edge adjacent said detector blade, means for mounting said detector blade for sliding movement along the cutting edge of said nipper blade to maintain said nipper blade sharp for severing the yarn.

3. A detector blade for a slab catcher comprising a pair of separate arms diverging at their 75

upper ends to provide a resilient fork, said arms being in contact along the major portion of the blade, and one of said arms having a notch to provide a slot between the arms for the passage of yarn therethrough.

5. In a slub catcher, a body frame having a contact bar over which the yarn is guided, a nipper blade having a sharp cutting edge mounted on said frame for movement toward said bar, a guard comprising an arm in front and an arm in back of said blade to prevent contact of said yarn with said cutting edge of the blade when in its position away from said bar, a detector blade having an opening through which the yarn travels, and means for mounting said detector blade for movement toward said nipper blade to engage and move said nipper blade to sever the yarn, said detector blade being located between said guard arms and between one guard arm and 20 nipper blade.

15. In a slub catcher, a body frame having a contact bar over which the yarn is guided, a nipper blade mounted on said frame for movement toward said bar, and a detector blade having an opening through which the yarn travels, said nipper blade being beveled to provide its cutting edge adjacent said detector blade means for mounting said detector blade to follow the traverse of the yarn and at the same time slide along 25 the cutting edge of said nipper blade to maintain said nipper blade sharp for severing the yarn.

20. In a slub catcher, a body frame having a contact bar over which the yarn is guided, a nipper blade mounted on said frame for movement toward said bar, and a detector blade having an opening through which the yarn travels, said nipper blade being beveled to provide its cutting edge adjacent said detector blade means for mounting said detector blade to follow the traverse 30 of the yarn and at the same time slide along the cutting edge of said nipper blade to maintain said nipper blade sharp for severing the yarn, said blades also being movable in the direction of the travel of the yarn to sever the yarn upon a 35 slub engaging said detector blade.

40. In a slub catcher, a body frame, a nipper blade, a saddle movably mounted on said body, a pair of relatively resilient arms extending from said saddle, and a detector blade, positioned

45. between said arms for moving said nipper blade, whereby removal of the detector blade is easily provided.

8. In a slub catcher, a body frame, a nipper blade, a saddle movably mounted on said body, a pair of relatively resilient arms extending from said saddle, each provided with locating bearing means for pivotally mounting the detector blade, and a detector blade having outwardly extending portions positioned between said arms located in 50 said bearing for moving said nipper blade, whereby removal of the detector blade is easily provided.

9. In a slub catcher, a body frame, a nipper blade, a saddle movably mounted on said body and provided with a plurality of openings, a coiled spring about said saddle having one end secured to the body and the other end relatively locatable in anyone of said plurality of openings to variably tension the spring and tend to rotate 20 the saddle in one direction, a detector blade positioned in said saddle for moving the nipper blade when engaged by a slub.

10. In a slub catcher a body frame having a pivot pin bearing, a nipper blade having a pivot pin receiving portion, a pivot pin removably positioned in said body frame bearing and blade to hingedly mount the same, a helical spring coiled about said pin and having one end engaging the body and the other end engaging said blade to 30 lift the blade, said spring being adjustable by withdrawal of the pin and winding the spring to provide more convolutions about said pin.

11. In a slub catcher, a body frame having a contact bar over which the yarn is guided, a nipper blade having a sharp cutting edge mounted on said frame for movement toward said bar, a guard comprising an arm in front and an arm in back of said blade to prevent contact of said yarn with said cutting edge of the blade when in its 40 position away from said bar, a detector blade having an opening through which the yarn travels, and means for mounting said detector blade for movement toward said nipper blade to engage and move said nipper blade to sever the yarn, 45 said detector blade being located between said guard arms and between one guard arm and nipper blade.

ROBERT V. OLSON.
